UNITED STATES PATENT OFFICE

119,864

DESIGN FOR A PLATE OR SIMILAR ARTICLE

Onnie Mankki, Cleveland, Ohio, assignor to Imperial Glass Corporation, Bellaire, Ohio, a corporation of Ohio

Application February 19, 1940, Serial No. 90,353

Term of patent 14 years

To all whom it may concern:

Be it known that I, Onnie Mankki, a citizen of the United States of America and resident of Cleveland, county of Cuyahoga and State of Ohio, have invented a new, original, and ornamental Design for a Plate or Similar Article, of which the following is a specification, reference being had to the accompanying drawing, forming part thereof, in which—

Figure 1 is a bottom plan view of a plate or similar article, showing my new design, and

I claim:

The ornamental design for a plate or similar article, substantially as shown.

ONNIE MANKKI.
